UNITED STATES PATENT OFFICE.

MAX SCHNUG, OF BONDUEL, WISCONSIN.

LEG-SETTING DEVICE.

1,176,491.

Specification of Letters Patent. Patented Mar. 21, 1916.

Application filed November 2, 1915. Serial No. 59,247.

To all whom it may concern:

Be it known that I, MAX SCHNUG, a citizen of the United States, and a resident of Bonduel, in the county of Shawano and State of Wisconsin, have invented certain new and useful Improvements in Leg-Setting Devices, of which the following is a specification.

My invention relates to portable means for setting a fracture of the lower leg of a human, either right or left, and the main object thereof is to provide such a device which may be readily assembled and unassembled whereby, when not in use, the parts will occupy but small space.

My present invention is a modification of the structure shown and described in an application for Letters Patent filed herewith and may employ certain portions thereof for the sake of economy in original outlay and to provide two distinct apparatus, one for the upper leg or hip and the other for the lower leg, with very few added parts and within one package of the unassembled parts.

Another object is to provide a base board which is provided with a detachable cross-head to balance the device and maintain the same in operative position.

Another object is to provide a tensioning screw having a bandage engaging head thereon by means of a swivel connection, whereby said head will not rotate in the rotation of the screw when tension is being applied to a fractured leg.

Another object is to provide means for preventing the rotation of the posts, and to provide cleats on said posts which are, because of said means, always maintained in desired relationship with the device. Cleats are double hooks which hold the strips which are on the other end fastened below the knee in place by simply winding them around the cleat. Requires no knot.

My invention is fully described in the following specification of which the accompanying drawings form a part, in which like characters refer to like parts in each of the views, and in which:

Figure 1 is a perspective view of my invention, ready for use; Fig. 2 is a section taken on the line 2—2 of Fig. 1; Fig. 3 is a section taken on the line 3—3 of Fig. 2; Fig. 4 is a section taken on the line 4—4 of Fig. 2; Fig. 5 is a fragmentary view of a detail.

In the drawings forming a part of this application, I have shown a base board 6 having a block 7 beneath one end and the other end of which is held between two blocks 8 on a cross-bar 9 of sufficient length to prevent tipping of the device when in use, the board 6 and bar 9 being readily detachable.

The board 6 is provided with a pair 10 of sockets adjacent one end and with a pair 11 of sockets adjacent the other end, the first pair of which is adapted to receive posts 12 and the other pair is adapted to receive posts 13, detachably, of relatively small height. Vertically adjustable upon the posts 12 by means of set-screws 14, are similar tubes 15 which enter and support a block 16 having a slot 17 formed therein for the reception of a longitudinally arranged bar 18.

The posts 13 are similarly provided with tubes 19 vertically adjustable by means of set-screws 20 and entering and supporting a block 21 provided with a slot 22 for the reception of the other end of the bar 18. The tubes 19 are provided, each, with a cleat 23 arranged to face away from the posts 12 and tubes 15, and in order to maintain this relationship I slot the upper ends of the tubes 19, as shown at 24, Fig. 5, transversely of the apparatus, and pass a rod 25 longitudinally through the block 21 and through the slots 24 of said tubes 19.

Vertically slideable on the tubes 15 is a block 26 adapted to be locked in adjusted position by means of set-screws 27, a screw 28 being threaded through said block 26 between the tubes 15 and parallel with the board 6, the outer end of the screw 28 being provided with a handle 29 and the inner end with a cross-head 30 swiveled thereto, as shown in Fig. 3, for bandage attachment.

In practice the injured leg has adhesive plaster straps fastened to the knee as well as to the foot end. These adhesive straps are fastened in such a way that they are held in position by the prominences of the bones at the knee as well as on the foot or ankle joint. These adhesive straps cannot slip and are strong enough to stand the pull which is necessary to set a fracture. In setting a fracture of the lower leg, it first receives the adhesive straps fastened at the knee and the foot end. The injured leg is then placed on the board 6. The upper part of the apparatus is now set together. After this is completed, the leg is lifted up

to the level of the cleats 23. The leg is then supported by two or more slings from bar 18 to hold the injured leg. After this is accomplished the fracture is set as follows: The adhesive straps fastened just below the knee joint are also fastened on both sides to the cleats 23 on posts 19, this holding the leg in one direction. The adhesive straps fastened to the foot are also fastened 10 to the part 30, the swivel head of the extension screw 28. By rotating the screw 28, the part 30 does not move with the screw and therefore does not hurt or twist the leg. The pull produced by rotation of screw 28 15 is gradual and therefore the extension produced this way to set the fracture gives only very little pain to the patient. The foot is also held in proper anatomical line by a sling support to bar 18. Having set the 20 fracture this way, the leg is held in place certain and tied, as if it was held in a vise. Now a final examination is made if everything is in the proper anatomical line and then the plaster cast or any other permanent 25 dressing is put on. If the plaster cast fits well, it is not necessary to put a weight on the foot to keep up extension. The leg can remain in the apparatus or may be removed and placed on a pillow. As pain to 30 the patient is hereby so much reduced, most fractures can be set without chloroform. Further there is plenty of room around the leg for dressing, so that it is practically as easy to treat a compound fracture as a simple 35 fracture with the aid of this apparatus.

The apparatus is extended on the foot end, so that the healthy leg cannot reach the cross bar 9. This cross bar 9 prevents tipping of the apparatus.

40 My apparatus is adapted for either leg and may be set up or knocked down in a few minutes and can be packed in a small parcel for transportation.

While the cleats and anti-rotation means 45 of tubes 19 are not shown in the application filled herewith, nor the means for vertical adjustment of the tubes, as shown herein, it will be obvious that I may employ them therein.

50 In practice, the injured leg is placed between the tubes 19, along the board 6, the tubes 19 being preferably out of operative position while the patient is being placed in position although not necessarily. A 55 bandage is now placed about the ankle of the injured leg and attached to the head 30, the screw 28 then being rotated to apply the desired tension to the leg, one or the other of the posts 13 bearing against the trunk 60 of the patient at the crotch between his legs to prevent movement toward the adjusting screw 28 while tension is being applied to the injured leg. One or more slings may now be suspended from the bar 18, to hold 65 the injured leg in convenient and comfort-

able position, and straps may be passed around the injured leg at or about the knee and led over the block 21 to the cleats 23 where they may be secured, thereby suspending the injured leg above the board 6 for 70 ease of passing the dressing bandages or for applying the plaster-cast, the required tension on the leg thus being taken by the adjusting screw and by the knee strap or straps and relieving the pressure of one of the 75 posts 13 against the patient. As the adjusting screw is rotated, it will be observed that the head 30 does not rotate and the bandage or strap connected therewith is not, therefore, twisted and the torsion of the injured 80 leg because of the adjustment of the tensioning screw is overcome.

My apparatus is adapted for either leg, and may be set up or knocked down in a few minutes and, as stated, I will make the 85 posts and tubes applicable to either this apparatus or to the one shown in the application for Letters Patent filed herewith, thus minimizing the number thereof, their weight, and the space occupied thereby when 90 packed for transportation.

While the cleats and anti-rotation means of the tubes 19 are not shown in the application filed herewith, nor the means for vertical adjustment of the tubes, as shown 95 herein, it will be obvious that I may employ them therein, or I may employ the specific forms shown therein in this form of apparatus, this being within my intent and within in the spirit of my invention.

Having fully described my invention, what I claim as new and desire to secure by Letters Patent is:—

1. A device of the class described, comprising a base board, a transverse bar thereunder and extending outwardly from each side thereof, a pair of tubes at one end thereof, a pair of tubes at the other end thereof, cleats on said last-named tubes, a block vertically adjustable on said first named tubes, a tensioning screw carried by said block, and a longitudinal bar joining the tops of the pairs of tubes.

2. A device of the class described, comprising a base board, a transverse bar extending from each side thereof, a pair of posts detachably connected with said board at one end thereof, a tube vertically adjustable on each post, a horizontally arranged tensioning screw vertically adjustable on said tubes, a pair of posts detachably connected with the other end of said board, a tube vertically adjustable on each of said last-named posts, a cleat on each of said last-named tubes, and a bar joining the tops of the pairs of tubes.

3. A device of the class described, comprising a base board, a transverse bar extending from each side thereof, a pair of posts socketed at one end of said board, a

5 tube vertically adjustable on each post, a tensioning screw vertically adjustable on said tubes, a block supported by said tubes, a pair of posts socketed at the other end of
5 said board, a tube vertically adjustable on each of said last-named posts, a block supported by said last-named tubes, a bar connected with both of said blocks, and a cleat
on each of said last-named tubes.

10 4. A device of the class described, comprising a base board, a transverse bar extending from each side thereof, a pair of posts socketed at one end of said board, a tube vertically adjustable on each post,
15 a tensioning screw vertically adjustable on said tubes, a block carried by said tubes, a

pair of posts socketed at the other end of said board, a tube vertically adjustable on each of said last-named posts, a cleat on each of said last-named tubes, a block carried by 20 said last-named tubes, means for preventing the rotation of said last-named tubes in said last-named block, and a bar connecting said blocks.

In testimony whereof I have signed my 25 name to this specification in the presence of two subscribing witnesses.
